UNITED STATES PATENT OFFICE

2,077,165

METHOD OF FRAMING HANDBAGS

Charles William Cheney, Birmingham, England

Application January 9, 1936, Serial No. 58,254
In Great Britain January 15, 1935

3 Claims. (Cl. 150—29)

The invention relates to an inlay of a bag, purse or the like.

An inlay and its use is very well known. Its cross-sectional shape is usually an inverted semi-circular U. It is a rigid structure of permanent shape, and is made of metal, and forms a clinched-on binding to the edges of one side and parts of two gussets of the material of which the bag, purse or the like, or a compartment therein, is composed, and when so applied is fixed within a rigid hinged frame-member of the bag or compartment.

Two inlays are used for one compartment, and two hinged-together rigid frame members form the frame of the compartment.

To apply such an inlay to the edges, aforesaid, requires a skilled worker, for the reason that the inlay is of a permanent rigid shape corresponding to the permanent rigid shape of the frame into which it has to fit, whereas the edges of the material are flexible and do not conform to the shape of the inlay when they are opened out flat. It therefore follows that the application of the inlay necessitates skilled and slow hand manipulation to gather-in the edges, and clinch the sides of the inlay down onto them.

Even when the gathering and clinching, aforesaid, are performed by a skilled worker there is unevenness in the gathering and in the clinching, causing irregular shapes in the gussets, and inadequate grip of the material by the inlay.

According to the invention a bendable inlay is provided of such a construction that it can be effectively attached to the material while the side wall and gusset portions are opened out into a flat condition, and can be subsequently bent to the shape of the rigid frame member arranged to receive it and to rigidly hold it. Said inlay comprises opposite side walls and a joining-up crown wall, and the side walls are provided with opposite cut-away parts permitting of the inlay bending at said cut-away parts.

The invention includes any construction of inlay which will permit of the inlay being clinched onto the edges of the opened out flat fabric, and of being subsequently bent to the shape of the frame. Where the side walls of the inlay are cut-away only bendable crown webs remain.

Such an inlay can be clinched to the edges of the material by unskilled labour, either by hand or between tools in a press.

It is preferable to so cut-away the side walls at the bendable parts that when the inlay is bent to the shape of the frame the edges of the cut-away parts will abut and support each other,

while, further, it is also preferable to provide a gap in one of the side walls, adjacent a bendable portion, to accommodate the upper adjacent portion of a closed-in gusset.

The invention and its use is illustrated by the accompanying sheets of drawings.

Fig. 1 is a side elevation of a sheet straightened out.

Fig. 2 is a transverse section of Fig. 1 on the dotted lines 2—2.

Fig. 3 is a transverse section of Fig. 1 on the dotted lines 3—3.

Fig. 4 is a transverse section of Fig. 1 on the dotted lines 4—4.

Fig. 5 is a side elevation of the inlay, Fig. 1, bent to a shape suitable for application to a frame.

Fig. 6 is a side elevation showing how the inlay is applied to the edge of the material.

Fig. 7 is a plan of Fig. 6, but showing two inlays applied.

Fig. 8 is a cross section of Fig. 6 on the dotted lines 6—6.

Fig. 9 is a side sectional elevation of the inlay applied to the bag frame.

Fig. 10 is a side elevation of a modified form of inlay.

Fig. 11 is a side elevation of a bag frame within which the inlay Fig. 10, is to be applied.

Fig. 12 is a side elevation of the bag to the edges of which the inlay Fig. 10, is to be applied.

Fig. 13 is a side elevation of a further modification of inlay.

Fig. 14 is a side elevation of a bag and bag frame within which latter the inlay Fig. 13, is to be fixed.

With reference to Figs. 1—9 an inlay 1, shaped up from a blank of metal, is of substantially inverted U cross-section having side walls 2 and 3 joined by a crown wall 4. Where bending is desired the opposite side walls 2 and 3 are cut away as shown at 5, leaving only bendable crown webs 6 at these cut-away parts. After the opened-out inlay has been applied to the edges, 7, of the side 8 and gussets 9 and 10, and has been bent to closed shape, tucking in the gusset portions, the edges of the cut-away parts 5, with the material pinched between them, will substantially abut and support each other, as clearly shown in Fig. 9.

A gap 11 in one of the side walls of the inlay, adjacent each of the bendable portions, is provided to accommodate the upper portion 12 of a closed-in gusset 13 clearly shown in Fig. 9, so that this gusset is directed from the frame 55

in a symmetrical manner and its formation does not impair the adequate and symmetrical bending of the inlay.

The intact portions of the side walls 2 and 3 5 are crinkled or serrated in staggered relation as shown at 14, to exert a grip on the material in the clinching operation, as represented by Fig. 8.

It will be clear from Figs. 6 and 7 of the drawings that the inlay is permanently applied to 10 the edges 7 of the material 8, 9 and 10 while the side and gusset portions are opened out flat, and from Figs. 5 and 9 that said inlay and material are subsequently closed in to the shape of the rigid frame member 15 into which the inlay is 15 fitted to be rigidly and permanently held.

The opened-out bendable inlay always conforms to the shape of the edges 7 of the opened out side and gusset portions so that it can be 20 easily, conveniently and securely attached, to be subsequently bent to the shape of the frame member; it being understood that, generally speaking, there are two hinged-together frame members 15 in a frame, whose opposite hinging points are represented at 16, 17.

25 The dotted lines 18, Fig. 9 indicate pins, or displaced portions, for rigidly fixing an inlay 1 within a frame member 15.

The modification, Fig. 10 represents a bendable inlay suitable for application to the edges 30 of the opened out bag or compartment material, Fig. 12, and for application to the rigid hinged frame, Fig. 11; similar numerals of reference being used on these three figures to indicate similar parts to Figs. 1 to 9.

35 The modification, Fig. 13 represents an inlay which will bend more than one way, and suitable

for a bag, or bag compartment, and a frame as represented in Fig. 14, the same numerals of reference being used in these two figures to indicate corresponding parts to Figs. 1-9.

Having now described my invention what I 5 claim and desire to secure by Letters Patent is:—

1. The herein described method of applying a metal inlay of U-shape cross section to the edge of the flexible material forming the gusseted compartment of a bag, purse or the like and 10 to the rigidly built frame of said bag, purse or the like, which consists in cutting away predetermined opposite portions of the side walls of the inlay to leave only the bendable crown webs between the adjacent rigid portions of the inlay, 15 fixing said inlay to said edge while said side wall and gusset parts are opened out flat by bending the inlay by hand to conform to the outline of the opened-out edges inserting said edges into said inlay, and thereafter clinching the sides of said inlay on to said edges, and finally bending the fixed inlay by hand to the outline of the rigid frame to receive it and fixing it therein.

2. The method of applying a metal inlay as 25 claimed in claim 1, which includes cutting the sides walls of the inlay so that the edges of the cutaway portions abut with the material pinched between them when the inlay is bent to the shape of the frame.

3. The method of applying a metal inlay as 30 claimed in claim 1, which includes cutting away more of one of the sides of the inlay inwardly of the places where the latter bends to form a gap to accommodate an adjacent upper portion of a 35 gusset.

CHARLES WILLIAM CHENEY.
